UNITED STATES PATENT OFFICE.

ROBERT DUNSEATH, OF NEW YORK, N. Y.

COLLAPSIBLE AND INTERCHANGEABLE BLOCK.

1,146,411.

Specification of Letters Patent. Patented July 13, 1915.

Application filed December 14, 1914. Serial No. 877,137.

To all whom it may concern:

Be it known that I, ROBERT DUNSEATH, a citizen of the United States, and a resident of New York, county and State of New York, have invented a certain new and useful Improvement in Collapsible and Interchangeable Blocks, of which the following is a full, clear, and exact specification.

This invention relates to a class of devices adapted to be used in the work of raising and lowering bodies especially of heavy weight.

My invention has for its object primarily to provide a block designed to be employed in conjunction with a cable or line whereby articles may be hoisted and lowered to and from various heights, and which is of a collapsible and interchangeable form to permit its parts to be detached from each other as well as allowing one or more of the parts to be replaced when damaged by wear or otherwise.

The invention consists essentially of a number of plates each having an opening in its center and a larger communicating opening therethrough. Through the large opening of each plate is guided a shaft having a plurality of spaced annular grooves in its periphery, and each plate is adjusted on the shaft so that the edge of its small opening will be removably seated in one of the annular grooves of the shaft, these grooves being of widths whereby the plates will be prevented from lateral movement on the shaft. Also on the shaft between each pair of the plates is a freely revoluble bushing having a freely rotatable sheave mounted thereon. The normal widths of each of the bushings and its sheave correspond approximately to the width of the part of the shaft between the annular grooves thereof on which they are mounted as well as conforming substantially with the space between the opposed plates so as to cause the bushings and the sleeves to revolve on a true line without lateral movement, thereby tending to equalize the wear of the bushings and the sheaves as well as preventing the plates from being forced tightly against the bushings and the sheaves which would bind these parts against free rotation.

Another object of the invention is to provide a shackle having a number of prongs one or more of which are movably held between the plates of the block to prevent the shackle and the plates from collapsible

movement when subjected to the strain of a heavy load; and a further object of the invention is to provide a simple and efficient block which may be made so as to combine great strength and durability.

With these and other objects in view the invention will be hereinafter more particularly described with reference to the accompanying drawings forming a part of this specification in which similar characters of reference indicate corresponding parts in all the views, and will then be pointed out in the claims at the end of the description.

In the drawings, Figure 1 is a front elevation of one form of collapsible and interchangeable block embodying my invention. Fig. 2 is a section taken on the line II—II of Fig. 1. Fig. 3 is a vertical sectional view taken through a block wherein a slightly different form of shaft is used in conjunction therewith. Fig. 4 is an elevation of one of the plates employed in the block, and Fig. 5 is a vertical section, partly in detail, through the shackle used in the block.

The collapsible and interchangeable block has two end plates 10, 11 and may have a suitable number of intermediate plates, as 12, 13, 14 therebetween, and these plates are adapted to be disposed in spaced parallel arrangement. All the plates may be elliptic or any other desired shapes, and the plates preferably correspond in size and thickness. Through the center of each of the plates 10, 11, 12, 13, 14 is an opening 15, and also through each plate is a larger opening 16 which communicates with the smaller opening. The communicating openings of all the plates are similar in size, and these communicating openings are arranged in the plates so as to register with each other when the plates are assembled. Through a corresponding part of the upper end portions of each of the plates is an opening 17, and likewise through a corresponding part of the lower end portions of each plate is a second opening 18.

In conjunction with the plates 10, 11, 12, 13, 14 of the block may be used either a graduated round shaft, as 19 Fig. 2, or a straight round shaft, as 20 Fig. 3. The graduated shaft 19 is of a length so that its ends will extend beyond the end plates of the block, and this shaft is formed of reduced portions 21, 22, 23, 24, the diameter of each of which may be of a suitable size relatively to the other reduced portions,

though the shaft is preferably made so that its reduced portions vary regularly from the largest portion at one of its ends to the smallest portion at its end, as shown, for instance the diameters of the portions, 21, 22, 23, 24 may be respectively $1\frac{1}{8}$ inches, $2\frac{1}{8}$ inches, $2\frac{3}{8}$ inches, $2\frac{5}{8}$ inches. In the periphery of the shaft 19 at the juncture of each of the reduced portions with its next adjacent portion are annular grooves 25, 26, 27, 28, 29, and the grooves are of depths whereby the parts of the shaft forming the bases of the grooves are of corresponding diameters. The annular grooves are slightly wider than the thickness of the plates 10, 11, 12, 13, 14 to allow the plates to be mounted therein, but prevent the plates from lateral movement, and the peripheries of the end parts of the shaft 19 which extend beyond the end plates 10 and 11 are threaded, at 30, to permit nuts 31 to be screwed thereon. The straight round shaft 20 is also of a length to extend some distance beyond the end plates of the block, and the peripheries of these extending parts of the shaft are threaded, at 32, to receive nuts 33 thereon. At spaced intervals in the periphery of the shaft 20 are annular grooves 34, 35, 36, 37, 38 all of which are of similar depths, and all of these grooves are of slightly greater widths than the thickness of the plates so that the plates when mounted therein will not move laterally.

On the shaft of the block in the spaces between the plates 10, 11, 12, 13, 14 are freely rotatable bushings 39, 40, 41, 42, all of which are circular in shape, and each bushing has a ring, or sleeve 43. Interiorly of each of the sleeves 43 is a bearing 44, and these bearings are preferably of well-known self-lubricating types made of copper having in the inner surfaces thereof spaced recesses containing a graphite lubricating material. In forms of the block where the grooved straight shafts 20 are used the bushings 39, 40, 41, 42 are similar in diameters while in the blocks where the grooved graduated shafts 19 are employed these bushings are formed to correspond in diameters by making the sleeves 43 thereof of different suitable thicknesses, as shown in Fig. 2, whereby the reduced portions 21, 22, 23, 24 of the shaft 19 will be compensated for so that the peripheries of the bearings will be in alignment. All of the bushings 39, 40, 41, 42 are of approximately the same widths as the widths of the shaft between its annular grooves so as to fit closely between the plates, but will revolve freely on the shaft.

On the bushings 39, 40, 41, 42 are freely revoluble sheaves 45, 46, 47, 48 all of which are preferably similar in diameter, and the openings through the centers of these sheaves are likewise similar in diameters.

In the opening of each of the sheaves 45, 46,

47, 48 is a fixed bearing 49, and these bearings are preferably of the same class as the bearings 44, being made of copper having in their inner surfaces spaced recesses containing a graphite lubricating material. The sheaves 45, 46, 47, 48 correspond in widths to the widths of the bushings 39, 40, 41, 42, and by making the sheaves and the bushings to conform substantially to the widths of the portions of the shaft between its grooves as well as conforming to the widths of the spaces between the plates 10, 11, 12, 13, 14, they will tend to revolve in a true line without lateral movement, thereby tending to equalize the wear thereof. Also by making the sheaves and the bushings to revolve separately the rotation of the sheaves will be insured in event of one or more of the bushings failing to revolve freely through any accidental cause.

When assembling either of the shafts, the sheaves, and the plates together one of the nuts is screwed on the threaded right end of the shaft, and the shaft is guided through the larger opening 16 of the end plate 11. The bushing 42 and the sheave 48 are applied on the shaft which is then passed through the larger opening of the intermediate plate 14, and the bushing 41 with the sheave 47 are mounted on the shaft, after which the shaft is passed through the larger opening in the plate 13. The bushing 40 with the sheave 46 are next applied on the shaft which is passed through the larger opening of the plate 12, and the bushing 39 with the sheave 45 are mounted on the shaft. The shaft is then passed through the larger opening of the end plate 10, and the second nut is screwed on the threaded left hand end of the shaft. The plates 10, 11, 12, 13, 14 are moved so as to register with the annular grooves of the shaft, and the plates are directed for the parts of the shaft forming the bases of the annular grooves thereof to be guided into the smaller communicating openings 15 of the plates. In this manner the plates will be detachably positioned on the shaft in spaced parallel arrangement as well as being held against lateral movement to prevent binding the bushings and the sheaves. When these parts of the block are assembled in each of the spaces between the upper ends of the plates 10, 11, 12, 13, 14 is arranged an apertured spacer or sleeve, as 50, so that the holes thereof will register with the holes 17 of the plates. A becket pin, or bolt, as 51, is guided through all of these registered holes, and these parts are tightened by accordingly screwing nuts 52 and 53 on the threaded ends of the pin.

In the lower end of the block is a removable shackle, as 54, which serves to allow an article or another block to be detachably connected thereto. The shackle 54 is formed with a plurality of spaced parallel disposed

- prongs 55, 56, 57, 58 extending from one of its ends, and while in the drawings are shown four of these prongs, forms of the shackle may be made having one or any suitable number of prongs. The prongs 55, 56, 57, 58 are of widths to adapt them to fit closely, but move freely between the plates of the block, and through the central parts of these prongs are registered openings 59.
- 10 When the shackle is mounted to the block the prongs are inserted in the spaces between the lower ends of the plates 10, 11, 12, 13, 14 so that the openings 59 thereof will be in register with the openings 18 of the plates.
- 15 A becket pin, or bolt 60 of a diameter to permit the block and the shackle to be relatively moved rotatably is passed through all of the registered openings, and by the use of nuts 61 and 62 on the threaded ends of the pin
- 20 the shackle will be removably held to the block. On the other end of the shackle, and extending in opposite directions as well as extending laterally with respect to the prongs, are two spaced parallel prongs, or fingers 63 and 64 having registered openings 65 and 66 respectively therethrough. In a part of the inner surface of the prong 63 is a recess 67 communicating with the opening 65, and the end of this recess within the
- 25 prong 63 serves as a stop 67a. Through a part of the prong 64 is a slot 68 communicating with the opening 66, and this slot is in register with recess 67 of the prong 63.
- In order to permit an article to be detachably connected to the prongs 63 and 64, in the openings 65 and 66 thereof is adjustably disposed a pin 69 which is of sufficient length so that both of its ends will extend beyond the sides of the prongs. Extending outwardly of the periphery of the pin 69 adjacent to one of its ends is a screw, or knob 70 which is of a size adapted to be guided inwardly and outwardly of the slot 68 and the recess 67 of the prongs 63 and 64. Through an opening 71 in the opposite end portion of the pin 69 is a cotter pin 72 or the like. The cotter pin 72 and the knob 70 are spaced apart so as to contact with the outer side surfaces of the prongs 63 and 64, and when
- 30 it is desired to attach an article to the shackle the adjustable pin 69 is rotated so that the knob 70 will pass through the slot 68 and into the recess 67 during the withdrawal of the pin outwardly of the openings 55 of the prongs 63 and 64 of the shackle. The knob will contact with the stop 67a of the recess 67, and the pin will be prevented from accidental loss by being held to the shackle. The article, for instance another
- 35 shackle as 73 with a single apertured prong as 74, is then placed between the prongs 63 and 64, and the pin is reversely guided through its openings of the prongs and through the recess 67 and the slot 68. When
- 40 the knob 70 has passed exteriorly of the slot

the pin is rotatably moved for contact with the prong 64, and the pin will thereby be held against accidental movement in the shackle. The provision of the shackle 54 in this form, and employing it in conjunction with the block in the manner described will obviate the tendency of the shackle and the plates of the block to any collapsible movement when subjected to the strain of a heavy load, and by making the block of the collapsible and interchangeable type as herein explained its parts are adapted to be detached from each other to allow one or more of the parts to be replaced when damaged by wear or otherwise.

In the foregoing description, I have embodied the preferred form of my invention, but I do not wish to be understood as limiting myself thereto, as I am aware that modifications may be made therein without departing from the principle or sacrificing any of the advantages of this invention, therefore I reserve to myself the right to make such changes as fairly fall within the scope of the appended claims.

Having thus described my invention, I claim as new and desire to secure by Letters Patent:—

1. A block of the character described, comprising a shaft having two spaced annular grooves in its periphery, two plates having registered openings through which the shaft is removably disposed, and the edge of each plate at its openings being seated in one of the grooves of the shaft to prevent the plates from lateral movement, a sheave rotatable on the shaft between the plates, means on the shaft to prevent accidental displacement of the shaft from the plates and from the sheave, and removable means on the plates to permit an article to be detachably connected to the block.

2. A block of the character described, comprising a shaft having two spaced annular grooves in its periphery, two plates having registered openings through which the shaft is removably disposed, and the edge of each plate at its opening being seated in one of the grooves of the shaft to prevent the plates from lateral movement, a bushing freely rotatable on the shaft between the plates, a sheave freely revoluble on the bushing, means on the shaft to prevent its accidental displacement from the plates and the bushing, and removable means on the plates to permit an article to be detachably connected to the block.

3. A block of the character described, comprising a shaft having a plurality of spaced annular grooves in its periphery, two plates having registered openings through which the shaft is removably disposed, and the edge of each plate at its opening being removably seated in one of the grooves of the shaft to prevent the plates from lateral

movement, a sheave on the shaft, between the plates, and the sheaves being approximately the same width as the space between the plates, means on the shaft to prevent accidental displacement of the shaft from the plates and the sheave, and a removable shackle on the plates to permit an article to be detachably connected to the block.

4. A block of the character described, 10 comprising a shaft having a plurality of spaced annular grooves in its periphery, two plates having registered openings through which the shaft is removably disposed, and the edge of each plate at its opening being 15 removably seated in one of the grooves of the shaft to prevent the plates from lateral movement, a freely revoluble bushing on the shaft between the plates, a freely revoluble sheave on the bushing, means on the 20 shaft to prevent accidental displacement of the shaft from the plates and the bushing, and a removable shackle on the plate to permit an article to be detachably connected to the block.

5. In a block of the character described, 25 two plates having centrally thereof registered corresponding openings, and having larger registered openings communicating with the smaller openings, a shaft having in 30 its periphery two spaced annular grooves of uniform depths, said shaft being first disposed through the larger registered openings of the plates and then guided into the smaller communicating openings so that 35 each plate will be removably seated in one of the grooves of the shaft, the grooves being of widths to prevent lateral movement of the plates, a sheave freely revoluble on the shaft between the plates, and means on 40 the shaft to prevent the shaft from accidental displacement with the plates and the sheave.

6. In a block of the character described, 45 two plates having centrally thereof registered corresponding openings, and having larger registered openings communicating with the smaller openings, a shaft having, in its periphery two spaced annular grooves of uniform depths, said shaft being first disposed through the larger registered openings of the plates and then guided into the smaller communicating openings so that each 50 plate will be removably seated in one of the grooves of the shaft, the grooves being of widths to prevent lateral movement of the plates, a bushing freely rotatable on the shaft between the plates, a sheave freely revoluble on the bushing, and means on the shaft to prevent the shaft from accidental 55 displacement with the plates and the bushing.

7. In a block of the character described, 60 two end plates and an intermediate plate all having centrally thereof registered corresponding openings, and having larger regis- 65

tered openings communicating with the smaller openings, a shaft having in its periphery three spaced annular grooves of uniform depths, said shaft being first disposed through the larger registered openings of 70 the plates and then guided into the smaller communicating openings thereof so that each plate will be removably seated in one of the grooves of the shaft, the grooves being of widths to prevent lateral movement of the 75 plates, two sheaves freely revoluble on the shaft, one between the intermediate plate and each of the end plates, and means on the shaft to prevent the shaft from accidental displacement with the plates and the sheaves, 80 and means to permit an article to be detachably connected to the block.

8. In a block of the character described, 85 two end plates and an intermediate plate all having centrally thereof registered corresponding openings, and having larger registered openings communicating with the smaller openings, a shaft having in its periphery three spaced annular grooves of uniform depths, said shaft being first disposed through the larger registered openings of the plates and then guided into the smaller communicating openings thereof so that each plate will be removably seated in one of the grooves of the shaft, the grooves being of 90 widths to prevent lateral movement of the plates, two freely revoluble bushings on the shaft, one between the intermediate plate and each of the end plates, two freely revoluble sheaves one on each of the bushings, and means on the shaft to prevent the shaft from accidental displacement with the plates and the bushings. 95

9. In a block of the character described, 100 two end plates and a plurality of intermediate plates all having centrally thereof registered corresponding openings, and having larger registered openings communicating with the smaller openings, a shaft having in 105 its periphery a plurality of spaced annular grooves of uniform depths, said shaft being first disposed through the larger registered openings of the plates and then guided into the smaller communicating openings thereof so that each plate will be removably seated in one of the grooves of the shaft, the grooves being of widths to prevent lateral movement of the plates, a plurality of freely revoluble bushings on the shaft, one in each space between the plates, a plurality of freely revoluble sheaves one on each of the bushings, all of the bushings and the sheaves being of widths corresponding approximately to the widths of the spaces between the plates, means on the shaft to prevent its accidental displacement with the plates and the sheaves, and a shackle on the plates to permit an article to be detachably connected to the block. 110

10. In a block of the character described, 115 two end plates and a plurality of interme- 120

diate plates all having centrally thereof registered corresponding openings, and having larger registered openings communicating with the smaller openings, a shaft formed
5 with graduated reduced portions, and having in its periphery spaced annular grooves one at the juncture of each reduced portion with its next adjacent reduced portion, said shaft being first disposed through the larger
10 registered openings of the plates and then guided into the smaller communicating openings thereof so that each plate will be removably seated in one of the grooves of the shaft, the grooves being of widths to prevent lateral
15 movement of the plates, a plurality of freely revoluble bushings one on each re-

duced portion of the shaft in each space between the plates, and said bushings being of graduated thicknesses so that the outer peripheries thereof are in alinement, a plurality of freely rotatable sheaves one on each of the bushings, means on the shaft to prevent its accidental displacement with the plates and the bushings, and means on the plates to permit an article to be detachably connected to the block. 20 25

This specification signed and witnessed this twelfth day of December A. D. 1914.
